DECORTICATING MACHINE

John S. Reeves, Baltimore, Md.

Application March 25, 1944, Serial No. 528,129

9 Claims. (Cl. 19—12)

1

This invention relates to decorticating machines particularly adapted for the production of fiber from the leaves of plants of the Agave family, such as Sansevieria, cabulla, Maya, pita flora, henequen, and the like.

The leaves of such plants are long and relatively narrow and contain longitudinal white fibers which can be recovered by cleaning away the pulp, juice, etc. In the usual machine this waste material, referred to as bagasse, is stripped from the leaves by scutching blades mounted on the periphery of a rotating wheel or drum. The leaves hang downwardly over an arcuate scutching face substantially concentric with the wheel, the blades exerting a squeezing and scraping effect which travels progressively along the leaves toward their free ends, stripping away the bagasse. The clearance between the scutching surface and blades must be very small to insure efficient cleaning, i. e., on the order of several thousandths of an inch.

To provide complete cleaning of the leaves from butt to tip, they are held first so that one end hangs down over the scutching face and this half of the leaf is cleaned, and then the leaves are automatically reversed and held by the cleaned fiber while the other end or half is being cleaned. The second cleaning operation may be accomplished by a second scutching wheel as in my prior Patent No. 2,341,290, or each leaf may be caused to pass the same scutching wheel twice, once for each end to be cleaned.

Machines of the types referred to above produce satisfactory cleaned fiber, but the mechanisms necessary for feeding the leaves past the scutching wheel or wheels and for handling the leaves and turning them end for end are undesirably complex and production and maintenance costs are correspondingly high. From the standpoint of quantity production, moreover, the output of cleaned fiber per machine is too low. The scutching blades engage the leaves near the middle and move toward the ends, so that the bagasse from the entire half of a leaf is stripped off ahead of the blades. This scutching action tends to cause breaking off of the fibers near the end of the leaf, decreasing both the amount and the length of the fiber produced. Further the capacity of the machine is limited because the danger of such breakage becomes rapidly greater as the speed of the scutching wheel is increased.

One of the objects of the present invention is to provide a novel apparatus of the class described above which is simpler in construction,

2

less expensive to construct and maintain, and capable of producing a greater yield of cleaned fiber substantially without breakage.

Another object is to provide an improved scutching action in which successive blades engage the leaf first at its end and then at points progressively farther from the end, the length of leaf subjected to scutching thus increasing by relatively small increments.

A further object is to eliminate the scutching face and wheel as heretofore known and to clean the leaves by passing them between flat relatively rotatable surfaces.

A still further object is to utilize the scutching movement of the blades for the additional purpose of feeding the leaves through the apparatus.

Still another object is to clean substantially the entire length of a leaf in one scutching operation.

Other objects will appear hereinafter as the description of the invention proceeds.

Broadly stated, apparatus embodying the present invention comprises relatively rotatable members one of which has a substantially flat scutching surface, the other member being provided with more or less radial scutching blades which project into close proximity with the scutching surface. Usually the scutching surface will comprise a stationary horizontal support and the blades will be carried by a rotatable member above the support, but the invention is not limited to this arrangement. The scutching support will also preferably cover only a part of the area of the circle of rotation of the rotating or upper member, being provided with a more or less radial edge which constitutes the feeding edge of the flat scutching surface. The shape and extent of this surface are otherwise immaterial, provided of course that it covers the scutching area.

The leaves are fed across the feeding edge end first and the rapidly rotating blades first engage and clean the tips of the leaves and then remove successive small sections of bagasse as the leaves advance, so that the cleaned fiber end gradually increases in length and the scutching action moves progressively up the leaves. At the same time the blades pull the leaves with them through the apparatus, the rate of feed of the leaves being controlled by holding the ends of the leaves against this pull. This may be done manually if desired, but usually it will be preferred to employ suitable mechanical gripping devices which move at the desired rate.

With a radial feeding edge, the direction of motion of the blades as they cross the feeding edge is at right angles to the edge so that the leaves are pulled into the machine. However, the direction of the feeding edge may depart considerably from the radial direction, provided that the direction of movement of the blades over the edge is such as to draw the leaves into the machine. As more and more of the leaf is cleaned, the cleaned fiber moves across the scutching area and also radially outward due to the tangential feeding action of the blades, being thus kept away from the center of rotation and discharged at the periphery of the machine.

Preferably the ends of the leaves are fed across the feeding edge at a point near the center of rotation, and the outer ends of the leaves are caused to move in a path which passes closely by the outer end of the feeding edge so that substantially the entire length of the leaf is cleaned in one pass through the machine. The angle between the longitudinal axis of the leaves and the feeding edge as the leaves are fed to the machine may vary considerably, and the direction of the path of movement of the outer ends of the leaves will be adjusted accordingly. However, the longitudinal axis of the leaves should not be transverse to the direction of movement of the blades as the leaves enter the scutching area, nor depart too far from parallelism with the direction, because of the danger of breaking or cutting off the fiber. For example, the angle between the direction of movement of the blades and the longitudinal axis of the leaf should not exceed say 45°, in which case the angle between the leaf axis and the feeding edge (if radial) must not be less than 45°.

One embodiment of the invention is illustrated in the accompanying drawings but it is to be expressly understood that said drawings are for purposes of illustration only and are not to be construed as a definition of the limits of the invention, reference being had to the appended claims for this purpose.

In the drawings,

Fig. 1 is a plan view of an apparatus embodying the invention, parts being broken away for clarity of illustration; and

Fig. 2 is a side view of the apparatus shown in Fig. 1.

The apparatus comprises any suitable framework here shown as having a bed plate 1 and uprights 2 suitably arranged to provide supports and bearings for the parts. The horizontal frame members 3 form a well 4 in which a hollow vertical post or column 5 is seated, this column carrying a horizontal flat scutching support 6 at its upper end. In the form shown, the support 6 has the shape of a sector of a circle, having a radial feeding edge 7 as above described and terminating at 8 (Fig. 1). A shaft 9 passes through the hollow column 5 and through the bottom of the well 4, the lower end of the shaft having a suitable step bearing 10 and the upper end rotating in a bearing 11 carried in the frame members 12.

The shaft 9 carries a rotating scutching member 13, the lower surface of which is provided with a plurality of projecting scutching blades 14. Preferably these blades 14 are generally radial in direction and cover substantially the entire lower surface of the member 13 as shown in dotted lines in Fig. 1. As shown in Fig. 2, the blades also project into close proximity to the scutching support 6 with their lower edges ro-

tating in a plane parallel and close to the scutching surface. Any suitable means may be provided for rotating the scutching member 13, preferably at a relatively rapid rate. As shown, the lower end of the shaft 9 carries a gear 15 meshing with an idler 16 which is driven by a pinion 17, bevel gears 18, 19, and a motor 20.

Leaves to be cleaned are fed to the apparatus in the position shown in Fig. 1 in which the tip 10 of the leaf passes over the radial feeding edge 7 at a point near shaft 9, the longitudinal axis of the leaf making an acute angle with the feeding edge. As the tip of the leaf passes over the feeding edge, it is immediately engaged by the inner ends of the scutching blades which draw the leaf farther into the scutching area while at the same time stripping the bagasse from the fiber. As the leaves move farther into the scutching area, the rotating scutching blades engage the leaf at 20 successively higher points in its length, each removing an additional portion of the bagasse therefrom. Meanwhile the cleaned fiber at the ends of the leaves moves both forward across the scutching area and radially outwardly as shown 25 in Fig. 1, due to the tangential action of the blades. As this action continues the outer end of the leaf, which is suitably held against the pull of the scutching action, travels past the outer end of the radial feeding edge and the cleaned fiber is discharged at the periphery of the machine, leaving only the small butt ends of the leaves uncleaned.

While as stated above the leaves may be fed manually to such an apparatus, it is preferred 35 in most cases to employ mechanical feeding means a suitable form of which is illustrated in the drawings. A series of moving leaf-supporting chains 21 are provided with upwardly projecting feeding fingers 22, groups or series of fingers on the several chains being arranged at the angle at which it is desired to present the leaves to the machine. The leaves are placed on a feeding table 23, the chain sprockets 24 operating beneath slots in the table so that the fingers 22 project above the table top and engage and slide the leaves off the table. At their opposite ends, the chains run on sprockets 25 which operate beneath slots formed in the scutching support 6 so that as the leaves are fed to the machine, the fingers 22 drop down beneath the scutching surface. The lower reaches of the chains 21 pass around idler sprockets 26 which may be adjustably mounted to regulate the slack in the chains. The chains may be driven in any suitable manner 55 and in the form shown the shaft 27 which carries the sprockets 24 also carries a drive sprocket 28 which is connected by a drive chain 29 with a sprocket 30 driven by a worm wheel 31 and a worm 32 on the shaft of the motor 20.

For the purpose of holding the outer ends of the leaves, a pair of chains 33, 34 are arranged one above the other on sprockets 35, 36, the lower sprocket 35 being mounted on the shaft 27 referred to above. The chains 33, 34 extend past the circumference of the rotating scutching member 13 and around sprockets one of which is indicated at 37 in Fig. 1, the sprockets 37 being geared together by pinions 38, 39 so that both chains are driven at the same speed. The chains carry pads which are suitably designed to engage and hold the butt ends of the leaves between them as the leaves are moved off the feeding table 23 and as they are carried forward toward the machine by the chains 21. Preferably the upper reach of the lower chain 33 moves on a support 40

and the lower reach of the upper chain 34 is pressed downwardly by a bar 41 which may be spring loaded as shown at 42.

When the leaves are discharged from the machine as described above, it will be seen that substantially the entire length of the leaf consists of cleaned fiber, leaving uncleared only the butt ends which are held between the chains 33, 34. If it is now desired to clean the butt ends of the leaves, a suitable supplemental mechanism may be combined with the machine above described. For example, the shafts of the sprockets 37 may also carry a pair of sprockets 43 which drive a pair of chains 44 similar to chains 33, 34. The sprockets 43 are located adjacent the periphery of the machine so that the cleaned fiber discharged therefrom is received between the chains 44, the butt ends of the leaves thereafter passing from engagement between the chains 33, 34 and hanging down from the chains 44. The butt ends may now be cleaned by a small scutching wheel 45 of known type which carries blades 46 and brushes 47 cooperating with a scutching support 48, the wheel being driven in any suitable manner as by a chain 49 and a motor 50.

It will be understood that the embodiment that has been described above with particularity and illustrated in the drawings is for purposes of example only and that the invention is not restricted thereto but is susceptible of a variety of mechanical expressions, many of which will now occur to those skilled in the art, and it will also be apparent that various changes may be made in the form, details of construction and arrangement of the parts without departing from the spirit of the invention. Reference should therefore be had to the appended claims for a definition of the limits of the invention.

What is claimed is:

1. Apparatus of the class described comprising a flat scutching support and a scutching member rotatable relative thereto and having blades projecting into close proximity with the surface of said support, said support having a feeding edge for leaves to be cleaned that is substantially radial relative to the axis of rotation of said scutching member.

2. Apparatus of the class described comprising a flat substantially horizontal scutching table, and a scutching member mounted to rotate above said table on a substantially vertical axis, said member having blades projecting into close proximity with the surface of said table, said table having a feeding edge for leaves to be cleaned that is substantially radial with respect to the axis of rotation of said member.

3. Apparatus of the class described comprising a flat substantially horizontal scutching table, a scutching member mounted to rotate above said table on a substantially vertical axis, said member having blades projecting into close proximity with the surface of said table, said table having a feeding edge for leaves to be cleaned that is substantially radial with respect to the axis of rotation of said member, and means for feeding leaves under said rotating member to said feeding edge.

4. Apparatus of the class described comprising a flat substantially horizontal scutching table, a scutching member mounted to rotate above said table on a substantially vertical axis, said member having blades projecting into close proximity with the surface of said table, said table

having a feeding edge for leaves to be cleaned that is substantially radial with respect to the axis of rotation of said member, and means for holding the outer ends of the leaves against the pull exerted thereon by the scutching blades.

5. Apparatus of the class described comprising a flat substantially horizontal scutching table, a scutching member mounted to rotate above said table on a substantially vertical axis, said member having blades projecting into close proximity with the surface of said table, said table having a feeding edge for leaves to be cleaned that is substantially radial with respect to the axis of rotation of said member, and means for holding the outer ends of the leaves against the pull exerted thereon by the scutching blades, said means being movable toward the feeding edge to control the rate of feed of the leaves.

6. Apparatus of the class described comprising a flat substantially horizontal scutching table, a scutching member mounted to rotate above said table on a substantially vertical axis, said member having blades projecting into close proximity with the surface of said table, said table having a feeding edge for leaves to be cleaned that is substantially radial with respect to the axis of rotation of said member, and means for feeding leaves under said rotating member to said feeding edge.

7. Apparatus of the class described comprising a flat substantially horizontal scutching table, a scutching member mounted to rotate above said table on a substantially vertical axis, said member having blades projecting into close proximity with the surface of said table, said table having a feeding edge for leaves to be cleaned that is substantially radial with respect to the axis of rotation of said member, means for feeding leaves under said rotating member to said feeding edge, and means for holding the outer ends of the leaves against the pull exerted thereon by the scutching blades.

8. Apparatus of the class described comprising a flat substantially horizontal scutching table, a scutching member mounted to rotate above said table on a substantially vertical axis, said member having blades projecting into close proximity with the surface of said table, said table having a feeding edge for leaves to be cleaned that is substantially radial with respect to the axis of rotation of said member, means for feeding leaves under said rotating member to said feeding edge, and means for holding the outer ends of the leaves against the pull exerted thereon by the scutching blades, said means being movable toward said edge to control the rate of feed of said leaves.

9. Apparatus of the class described comprising a flat substantially horizontal scutching table, a scutching member mounted to rotate above said table on a substantially vertical axis, said member having blades projecting into close proximity with the surface of said table, said table having a feeding edge for leaves to be cleaned that is substantially radial with respect to the axis of rotation of said member, means for feeding leaves under said rotating member to said feeding edge, and means for holding the outer ends of the leaves against the pull exerted thereon by the scutching blades, said means being movable toward said edge and past the periphery of rotation of said member at one side thereof.

JOHN S. REEVES,
